UNITED STATES PATENT OFFICE.

CHARLES H. WEST, OF PITTSBURGH, PENNSYLVANIA, ASSIGNOR TO WESTMORELAND SPECIALTY COMPANY, OF GRAPEVILLE, PENNSYLVANIA, A CORPORATION OF PENNSYLVANIA.

DESIGN FOR AN ORNAMENTAL BOWL OR SIMILAR ARTICLE.

Application filed January 19, 1922. Serial No. 262. Term of patent 3½ years.

To all whom it may concern:

Be it known that I, CHARLES H. WEST, a citizen of the United States, residing at Pittsburgh, in the county of Allegheny and State of Pennsylvania, have invented a new, original, and ornamental Design for an Ornamental Bowl or Similar Article, of which the following is a specification, reference being had to the accompanying drawing, forming part thereof.

Fig. 1 of the drawing is a plan view showing my new design; and

Fig. 2 is a perspective view thereof, the upper portion of the bowl being in contrast with its body portion and the decorative lines being distinctively applied.

I claim:

The ornamental design for an ornamental bowl or similar article, as shown.

CHARLES H. WEST.
